(57) **CLAIM**

The ornamental design for a spray cabinet, as shown and described.

DESCRIPTION

FIG. 1 is a front left perspective view of a spray cabinet in accordance with another embodiment of the claimed design; FIG. 2 is the design of FIG. 1 in an open position; FIG. 3 is a front elevation view of the design of FIG. 1; FIG. 4 is a right side elevation view of the design of FIG. 1; FIG. 5 is a left side elevation view of the design of FIG. 1; FIG. 6 is a top plan view of the design of FIG. 1; and, FIG. 7 is a bottom plan view of the design of FIG. 1.

The rear elevation views of the designs of FIG. 1 is omitted as they form no part of the claimed design and/or are cumulative in view of the remaining figures.

The dash-dash broken lines in the figures (e.g., including at least the fasteners and bolts) represent unclaimed subject matter and form no part of the claimed design.

The dot-dash broken lines in the figures immediately adjacent the solid lines represent a boundary between claimed and unclaimed subject matter and form no part of the claimed design.

The labels used herein to describe orientation (e.g., front, rear, left, right) are merely for reference and are not intended to limit the interpretation of the design.

Applicant reserves the right to convert a portion or portions of any of the broken lines to solid lines such that the features described by those lines then form a part of the claimed design; and/or to convert a portion or portions of any of the solid lines to broken lines such that the features described by those lines no longer form part of the claimed design.
